(57) **CLAIM**

The ornamental design for a tape cartridge for label printing machine, as shown and described.

DESCRIPTION

FIG. 1 is a top view of the tape cartridge for label printing machine;

FIG. 2 is a bottom view thereof;

FIG. 3 is a front view thereof;

FIG. 4 is a rear view thereof;

FIG. 5 is a left view thereof;

FIG. 6 is a right view thereof;

FIG. 7 is a perspective view thereof the right end; and,

FIG. 8 is a perspective view thereof from the left end.
